BRUSH WIPER ATTACHMENT FOR
CONTAINERS

Dominick J. Coyliondro, Port Chester, N. Y.

Application October 23, 1941, Serial No. 416,272

1 Claim. (Cl. 220—90)

This invention relates to a brush wiper for containers containing liquids, pastes or the like to be applied by means of a brush and provides means for wiping excess liquid from the brush head after it has been dipped into contents of the container and so that the liquid thus removed will drip back into the container.

More particularly, it is the aim of the invention to provide such an article which is formed from a single strand of wire having a portion for frictionally engaging the inner side of a container wall for supporting the article therein, and one or more bar or rod portions which are spaced from the container wall and on which the brush head can be wiped.

Other objects and advantages of the invention are:

To provide a wiper which will effect a saving in liquid or other material being applied with a brush by returning all the liquid or other material wiped from the brush back to the container; to provide an attachment that can be applied to the container when it is filled and which can be so disposed in the container that it will not interfere with the cover being applied thereto and which will prevent paint or other liquid from accumulating in groove of the container which receives the cover; to provide a device which will form convenient means for supporting a brush when not in use in a position so that the liquid thereon will drip into the container and which, when used for wiping brush head, will prevent any of the liquid wiped therefrom from accumulating in the cover receiving channel of the container or running down the outer side thereof; to provide a device that can be used for holding a mixing stick or small brush while the liquid is being applied from the container with a larger or another brush; to provide an article which can be readily pushed down into the container or to a position adjacent the top thereof without removing the contents of the container; and to provide a straight surface which is substantially round in cross-section on which the bristles of the brush can be wiped for removing excess liquid therefrom and which will therefore evenly clean the brush head and will not injure the bristles near the edges thereof as occurs when the bristles are wiped against the curved upper edge of a container.

The invention will hereinafter be described in conjunction with a conventional paint can and it is to be understood that it is adapted to be used with other types of containers adapted to contain any liquid, paste or the like which can

be applied with a brush such as varnishes or shellacks, glue, mucilage, liquid tar, roofing preparations and the like.

Other objects and advantages of the invention will hereinafter become more fully apparent from the following description of the drawing, which illustrates a preferred embodiment thereof, and wherein:

Figure 1 is a top plan view of the attachment shown in an applied position in a container, which is shown in horizontal section and substantially along a plane as indicated by the line 1—1 of Figure 2. Figure 2 is a vertical sectional view, on a reduced scale, of a portion of the container and attachment taken substantially along a plane as indicated by the line 2—2 of Figure 1, and

Figure 3 is a similar view taken substantially along a plane as indicated by the line 3—3 of Figure 1.

Referring more particularly to the drawing, wherein like reference characters designate like or corresponding parts throughout the different views, 10 designates generally the upper portion of a conventional can of the type generally employed for containing paint, varnish, shellac and similar liquids, paste or the like which are intended to be applied with a brush. The can 10 has a cylindrical side wall 11 which is turned inwardly at its upper end and in such inwardly turned portion is formed a downwardly offset annular channel 12 which is adapted to receive a rim of a cover or lid, not shown. The inner annular wall 13 of channel 12 forms the opening 14 in the top of the can 10. The outer annular wall 15 of the channel 12 is spaced from the can wall 11 and combines therewith to form an annular outwardly opening channel or groove 16. The parts 11 to 16 of the can 10 are of conventional construction and have been shown and described merely to better illustrate a preferred application of the brush wiper attachment, designated generally 17, and comprising the invention.

The wiper attachment 17 is formed from a single strand of wire including generally an intermediate portion, designated generally 18, end portions, designated generally 19 and 20, and portions 21 and 22 which connect corresponding ends of the portions 19 and 20 to the ends of the intermediate portion 18. The intermediate portion 18 and the end portions 19 and 20 each include a substantially straight intermediate portion 23 and substantially straight end portions 24 which are angularly disposed relatively to their intermediate portions 23. The portions 21

and 22 are each provided with downwardly offset portions 25 at their ends and substantially straight intermediate portions 26 disposed therebetween and in substantially the same plane as the intermediate portion 18 and the end portions 19 and 20.

The attachment 17 is normally disposed in the can 10 and with end of the intermediate portions 23 and end portions 24 of portions 18, 19 and 20 in engagement with the inner side of the cylindrical wall 11. The attachment 17 is of such a size that said ends will frictionally engage the can wall 11 to support the attachment 17 in the can 10. By grasping the portion 26 the attachment 17 can be drawn upwardly to position its portions 18, 19 and 20 within the downwardly opening channel or groove 16 and when thus disposed the intermediate part of the portions 23 will then frictionally engage the outer side of the annular wall 15 to more effectively retain attachment 17 in its applied position, as shown. When thus disposed, the downwardly offset portion 25 will be disposed beneath the channel 12 and the portions 26 will extend across parts of the can opening 14. It will thus be readily apparent that the portions 26 will form substantially straight rods or bars which are substantially circular in cross-section and which are disposed in the can opening 14 so that the brush 27, as seen in dotted lines in Figure 3, can be wiped or stroked on either of the wiper or stroke bars or rods 26, after being dipped in the content of the can 10, for removing excess paint or other liquids therefrom. It will furthermore be readily obvious that the paint thus removed will drip back into the can 10 and cannot accumulate in the channel 12 or flow down the outer side of the can 10. Furthermore the straight bars or rods 26 will form a straight surface on which the bristles of the brush 27 can be wiped so that all parts of the brush head will be wiped evenly thereon and so that there will be little or no wear on the bristle as occurs when a brush is wiped on the rounded upper edge of a can.

It will likewise be readily obvious that a lid could be applied to the open top of the can 10 with the attachment 17 disposed therein so that

said attachment can be applied when the can is filled originally so as to form part of the can when sold to the ultimate consumer. If desired, attachment 17 can be pushed down into the can 5 and thereafter again raised to its position, as illustrated, without removing the contents from the can.

Obviously, the attachment 17 could be applied to any can which is not provided with a channel 12 or could be mounted in a jar, pail or any other receptacle used for holding liquids to be applied with a brush.

One of the bars or rods 26 can also be used for holding a mixing stick and a small paint brush 15 in the space between said bar and the adjacent portion of the wall 13 while paint is being applied with another paint brush. Likewise the head of the brush 27 could be rested on the two bars 26 so that any paint dripping therefrom drops into 20 the can 10.

Various modifications and changes are contemplated and may obviously be resorted to, provided they fall within the spirit and scope of the invention as hereinafter defined by the appended 25 claim, as only a preferred embodiment of the invention has been disclosed.

I claim as my invention:

A brush wiper attachment of wire for application to a container having a U-shaped depressed ring outwardly of its pouring opening, and inwardly spaced from the side wall, said wire having a straight portion adapted to extend across the ring in chordal relation thereto, each end of said straight portion having a downwardly extending U-shaped part providing vertical walls for engagement with the ring at said mouth, and the wall in said space, each of said U-shaped portions having integral therewith an extension provided with a plurality of angularly related straight sections lying substantially in the plane of the first straight portion, each of said extensions being adapted to lie in the space between said ring and well and adapted to contact the opposite wall thereof in gripping relation.

DOMINICK J. COYLONDRO.
